CLAIM

The ornamental design for a device charger with folding power plug and micro USB connections, as shown and described.

DESCRIPTION

FIG. 1 is a perspective view of an device charger with folding power plug and micro USB connections taken from the top, right, and front, and illustrating a first orientation;

FIG. 2 is another perspective view of the device charger with folding power plug and micro USB connections taken from the bottom, left, and front, and illustrating a second orientation;

FIG. 3 is a perspective view similar to FIG. 2 but showing the device charger with folding power plug and micro USB connections as it appears when the electrical contact prongs of the folding power plug are in an unfolded position;

FIG. 4 is a top plan view of the device charger with folding power plug and micro USB connections of FIG. 1;

FIG. 5 is a bottom plan view of the device charger with folding power plug and micro USB connections of FIG. 1;

FIG. 6 is a left side elevation view of the device charger with folding power plug and micro USB connections of FIG. 1;

FIG. 7 is a left side elevation view similar to FIG. 6 but showing the device charger with folding power plug and micro USB connections as it appears when the electronic contact prongs of the folding power plug are in an unfolded position;

FIG. 8 is a right side elevation view of the device charger with folding power plug and micro USB connections of FIG. 1;

FIG. 9 is a front elevation view of the device charger with folding power plug and micro USB connections of FIG. 1; and,

FIG. 10 is a back elevation view of the device charger with folding power plug and micro USB connections of FIG. 1.

The broken lines are directed to environment and are for illustrative purposes only. The broken lines form no part of the claimed design.
